US00D860653S

(12) **United States Design Patent** (10) **Patent No.:** **US D860,653 S**
(45) **Date of Patent:** **** Sep. 24, 2019**

(54) **TOOTHBRUSH**

- (71) Applicant: **COLGATE-PALMOLIVE COMPANY**, New York, NY (US)
- (72) Inventors: **Wenjin Xi**, Shanghai (CN); **Yanmei Ji**, Yangzhou (CN); **Bo Zhang**, Yangzhou (CN); **Kai Zhang**, Yangzhou (CN); **Guangsheng Guo**, Yangzhou (CN)
- (73) Assignee: **Colgate-Palmolive Company**, New York, NY (US)
- (**) Term: **15 Years**
- (21) Appl. No.: **29/625,816**
- (22) Filed: **Nov. 13, 2017**

Related U.S. Application Data

- (62) Division of application No. 29/570,680, filed on Jul. 11, 2016, now Pat. No. Des. 813,550, which is a division of application No. 29/498,171, filed on Jul. 31, 2014, now Pat. No. Des. 764,177.

(57) **CLAIM**

The ornamental design for a toothbrush, as shown and described.

DESCRIPTION

FIG. 1 is a right front perspective view of a toothbrush according to an embodiment of the new design; FIG. 2 is a left rear perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof. The dashed lines shown in the drawings illustrate environmental structure that form no part of the claimed design. The dash-dot-dashed lines directly adjacent to the claimed areas are included to represent the boundaries of the claimed design and form no part of the claimed design.

1 Claim, 4 Drawing Sheets
